UNITED STATES PATENT OFFICE.

FRANK P. READ AND WYCKLIFFE W. PARSONS, OF CHICAGO, ILLINOIS.

DESIGN FOR A COMBINED PHONOGRAPH-CABINET AND HALL-CLOCK CASE.

52,194.

Specification for Design.

Patented July 16, 1918.

Application filed June 19, 1917. Serial No. 175,700. Term of patent 14 years.

To all whom it may concern:

Be it known that we, FRANK P. READ and WYCKLIFFE W. PARSONS, citizens of the United States, residing at Chicago, in the county of Cook and State of Illinois, have invented a new, original, and ornamental Design for a Combined Phonograph-Cabinet and Hall-Clock Case, of which the following is a specification, reference being had to the accompanying drawing, forming a part thereof.

The figure is a perspective view of a combined phonograph cabinet and hall clock case, showing our design.

Copies of this patent may be obtained for five cents each, by addressing the "Commissioner of Patents, Washington, D. C."

We claim:

The ornamental design for a combined phonograph cabinet and hall clock case, as shown.

In testimony whereof we have signed our names to this specification in the presence of two subscribing witnesses.

FRANK P. READ.
WYCKLIFFE W. PARSONS.
